UNITED STATES PATENT OFFICE.

EMIL JAGENBERG, OF DUSSELDORF, GERMANY.

PAPER-FEEDING APPARATUS

1,096,539.

Specification of Letters Patent. Patented May 12, 1914.

Application filed July 30, 1913. Serial No. 781,906.

To all whom it may concern:

Be it known that I, EMIL JAGENBERG, a subject of the German Emperor, and residing at 107 Himmelgeisterstrasse, Dusseldorf, Germany, have invented certain new and useful Improvements in Paper-Feeding Apparatus, of which the following is a specification.

The present invention relates to an arrangement for removing the cardboard sheets from the pile in cardboard box making machines and the like. Hitherto the sheets were removed singly from the pile by a slide pushing them through a stationary slot, the width of which corresponded to the thickness of the sheet. These arrangements, however, work properly only as long as the cardboards in the pile are straight and level. When these cardboards are curved or warped, and this occurs very frequently, the edge of the foremost sheet to be removed will not meet the slot, and the sheet is then frequently crumpled up by the advancing slide. This trouble is obviated by the present invention, which consists in that the slot, through which the sheets are to pass, is so displaceable, that it will automatically adjust itself exactly under the edge of the foremost sheet to be advanced.

The present invention is exemplified in the accompanying drawing.

Figure 1 is a longitudinal section and Fig. 2 is a plan of the arrangement.

The piled cardboard sheets *a* are pressed by the ram *b* against the vertically reciprocable slide *c*. The slide *c* moves in the guide *d* and has a tongue *f*, which, on the slide descending, will settle on the upper edge of the foremost sheet and press the latter downward off the pile. This tongue may be adjusted by means of a screw *g*; and only the upper edge of the sheet will bear against the slide, so that it is possible for the slide to remove also curved or warped sheets. Below the sheets are forced against a narrow, flat spring *h* which is attached to a wide horizontally reciprocable plunger *i*. The flat spring is arranged opposite to a centrally disposed curved ledge *k*, which is likewise attached to the plunger in such a manner that these two parts form between themselves a narrow slot *m* which is narrower in the middle and wider at the ends. The plunger is guided with the shoulder *n* in

the top of the machine and is drawn by means of a spring *o* toward the ram *b*. The upper end of the flat spring *h* is slightly curved and supported by a set screw *p*, by means of which the width of the slot *m* may be varied according to the thickness of the cardboard sheets. The sheets are forced by the ram with their lower edges against the flat spring *h*, and the latter then recedes under their pressure, together with the plunger *i* at the same time tightening the spring *o*. The lower edge of the foremost sheet will therefore always be exactly over the slot *m*, so that this sheet can be pushed downward by means of the tongue *f*.

As the width of the slot *m* is only in its middle portion as narrow as the thickness of the sheet, and this portion is short, also wide and curved sheets can be removed, as the wide slots at the side *r* allow of the sheets passing through. The springs *s* provided in the slots *r* at the sides and converging below, and the ledges *t* will then straighten the sheets.

I claim:

1. A paper feeding apparatus comprising an upright slide, a tongue on the slide adapted to engage the upper edge of a paper sheet, a horizontally movable plunger below said sheet, said plunger being provided with a centrally disposed curved ledge and a spring opposite said ledge, said ledge and spring forming conjointly a paper discharge slot, that increases in width from the center toward both of its ends.

2. A paper feeding apparatus comprising an upright slide, a tongue on the slide adapted to engage the upper edge of a paper sheet, a horizontally movable plunger below said sheet, said plunger being provided with a centrally disposed curved ledge and a spring opposite said ledge, said ledge and spring forming conjointly a paper discharge slot, that increases in width from the center toward both of its ends, and plungers and additional springs within said ends.

100

In testimony whereof I have hereto affixed my signature in the presence of two witnesses.

EMIL JAGENBERG, [L. s.]
